A. A. Vanall
His attorney

UNITED STATES PATENT OFFICE.

ROBERT M. GILSON, OF PITTSBURGH, PENNSYLVANIA, ASSIGNOR TO THE UNION
SWITCH & SIGNAL COMPANY, OF SWISSVALE, PENNSYLVANIA, A CORPORATION
OF PENNSYLVANIA.

RAILWAY-TRAFFIC-CONTROLLING APPARATUS.

Application filed July 21, 1927. Serial No. 207,422.

My invention relates to railway traffic controlling apparatus, and particularly to apparatus of the type comprising train-carried governing mechanism controlled by energy supplied from the trackway. More specifically, the present invention relates to the trackway portion of such apparatus.

I will describe one form of apparatus embodying my invention, and will then point out the novel features thereof in claims.

The accompanying drawing is a diagrammatic view showing one form of trackway apparatus embodying my invention.

Referring to the drawing, the reference characters 1 and 1^a designate the track rails of a railway along which traffic normally moves in the direction indicated by the arrow. These rails are divided by insulated joints 2 into a plurality of successive track sections, of which three complete sections D—E, E—F and F—K are shown in the drawing.

Each track section is provided with a track circuit comprising a track battery 3 connected with the rails adjacent the exit end of the section, and a track relay connected with the rails adjacent the entrance end of the section and designated by the reference character G with an exponent corresponding to the location. Each track battery is connected across the rails through a limiting impedance 6 and the secondary 4 of a transformer designated by the reference character T with an exponent corresponding to the location. The function of the transformers T will appear hereinafter.

Located adjacent the entrance end of each section is a signal designated by the reference character S with an exponent corresponding to the location, each of which signals, in the form here shown, is of the three-position semaphore type, capable of indicating proceed, caution and stop. These signals are controlled in such manner that when a section is occupied the signal for such section indicates stop, the signal for the first section in the rear indicates caution, the signal for the second section in the rear indicates caution, and the signal for the third section in the rear indicates proceed. The apparatus for controlling these signals has

nothing to do with my present invention and is omitted from the drawing to simplify the disclosure. One form of apparatus for controlling the signals in the manner stated, is disclosed in application for Letters Patent of the United States by Herbert A. Wallace, filed August 21, 1924, Serial No. 733394, for railway traffic controlling apparatus.

Each section is provided with means for supplying alternating train governing current to the track rails, which current is periodically interrupted at one frequency or another according to traffic conditions in advance. As here shown, the periodic interruption of the alternating current for each section is controlled by a coding device designated by the reference character C with an exponent corresponding to the location, each of which devices comprises a motor 9 which operates two cams 10 and 11. The cam 10 controls a contact 12 in such manner that this contact is opened once for each revolution of the cam, and the cam 11 controls a contact 13 in such manner that this contact is opened three times for each revolution of the cam.

The supply of operating current to the motor 9 of each coding device is controlled by a relay designated by the reference character A with an exponent corresponding to the location, each of which relays is normally de-energized. Referring specifically to relay A^E for section D—E, this relay is provided with a main circuit which passes from terminal X of a suitable source of current through back contact 17 of track relay G^D, contact 16 operated by signal S^D, and the winding of relay A^E to terminal Y of the same source of current. Contact 16 is closed when signal S^D indicates proceed, but not when this signal indicates caution or stop. The relay A^E is provided with an auxiliary circuit which passes from terminal X, through back contact 8 of a slow-releasing relay H^D, and winding of relay A^E to terminal Y. The slow releasing relay H^D is provided with a circuit which passes from terminal B of a suitable source of direct current through front contact 7 of track relay G^D, and the winding of relay H^D to terminal O of the same source of current. It

will be seen from the foregoing that relay A^E is de-energized when section D—E is unoccupied, and that relay A^E becomes energized when a train enters section D—E. It will also be noted, however, that if signal S^D is in the proceed position when a train enters section D—E, relay A^E becomes energized as soon as the train enters the section, but that if signal S^D is in the caution or the stop position, the energization of relay A^E is delayed for a period of time determined by the time required for the back contact 8 of relay H^D to close.

Each of the remaining relays A is controlled by apparatus similar to that which controls relay A^E .

Each section is provided with a line relay designated by the reference character L with an exponent corresponding to the location, and each of which line relays is controlled by the track relay for the associated section and by the track relay for the section next in advance. Referring for example to line relay L^E , the circuit for this relay is from terminal X, through front contact 18 of track relay G^F , front contact 19 of track relay G^E , and the winding of relay L^E to terminal Y. Each line relay L^E is provided with a contact 14 which determines whether the supply of train governing current for the associated section shall be interrupted by contact 12 or contact 13 of the associated coding device C. Again referring specifically to section D—E, I will assume that line relay L^E is energized, and that relay A^E is also energized. Alternating current then flows from terminal X, through contact 15 of relay A^E , contact 13 of coding device C^E , front contact 14—14^a of relay L^E , and the primary 5 of transformer T^E to terminal Y. The alternating current then supplied to the rails of section D—E is periodically interrupted by contact 13 at such rate that this current will give a proceed indication aboard a train, and the current thus supplied to the rails may be termed the proceed code. If, however, either section E—F or F—K is occupied, line relay L^E will be de-energized, and the circuit just traced for the primary 50 of transformer T^E will then be open at front contact 14—14^a so that the primary of transformer T^E will be supplied with train governing current through contact 12 of coding device C^E and back contact 14—14^b of relay L^E . The train governing current will then be interrupted at such rate as to cause a caution indication on the train occupying section D—E, and so this current may be termed the caution code.

60 The apparatus shown in the accompanying drawing is intended for co-operation with train-carried governing mechanism which is controlled by the periodically interrupted train governing current in the track rails in such manner as to give a pro-

ceed indication in response to the proceed code, and a caution indication in response to the caution code. The train-carried governing mechanism is further controlled in such manner that upon a change from a proceed to a caution indication, a brake application will result or a stop indication will be given unless the engineer takes suitable steps to acknowledge such change of indication. Furthermore, the control of the train-carried governing mechanism is such that if the periodic supply of train governing current of the caution code is temporarily interrupted, a brake application will result or a stop indication will be given unless the engineer again takes suitable action to acknowledge the temporary discontinuance of train governing current. One form of train-carried mechanism which will operate in the manner just described, is disclosed in application for Letters Patent of the United States, filed by Lloyd V. Lewis on August 2, 1927, Serial No. 210165, for railway traffic controlling apparatus.

As shown in the drawing, the section immediately to the right of point K is occupied by a train represented by an axle and pair of wheels W, so that signal S^K indicates stop and both signals S^F and S^E indicate caution, while signal S^D indicates proceed. I will assume that a second train equipped with governing mechanism of the type hereinbefore described approaches section D—E, and that the section immediately in the rear of this section is receiving train governing current of the proceed code. As the train enters section D—E, it will de-energize track relay G^D , and inasmuch as contact 16, operated by signal S^D , is closed, relay A^E will become energized as soon as the train enters the section. Relay L^E is energized, so that train governing current periodically interrupted in accordance with the proceed code will be supplied to the rails of section D—E and this supply will begin as soon as the train enters the section. No change will occur in the train-carried mechanism, and so no acknowledgment on the part of the engineer will be required. As the train enters section E—F, the energization of relay A^F will be delayed, because contact 16 on signal S^E is open. Relay L^F is de-energized, so that train governing current of the caution code will be supplied to the rails of this section. Due to the change of indication, and also due to the delay in supplying train governing current to the rails after the train enters the section, the engineer must acknowledge upon entering section E—F or he will be penalized by a brake application or a stop indication. When the train enters section F—K, it will still receive train governing current of the caution code, because line relay L^K is open, but the supply of this current will be delayed due to the fact that

contact 16 on signal S^F is open. It will be noted that there is no change in the indication given aboard the train as the train enters section F—K, so that if current of the caution code were supplied to this section as soon as the train enters the section it would not be necessary for the engineer to acknowledge the caution signal S^F . Inasmuch, however, as circuit controller 16 is open, the supply of current of the caution code will be delayed for a short interval of time after the train enters section F—K, which interval is of sufficient length to restore the train-carried mechanism to its normal condition, thus requiring the engineer to acknowledge signal S^K in order to prevent a brake application or a stop indication aboard the train.

Although I have herein shown and described only one form of apparatus embodying my invention, it is understood that various changes and modifications may be made therein within the scope of the appended claims without departing from the spirit and scope of my invention.

Having thus described my invention what I claim is:

1. In combination, a section of railway track, means for supplying train governing current to said section when and only when the section is occupied by a train and for normally starting the supply of such current as soon as a train enters the section, and means for delaying the supply of said current to the section when a train enters the section if traffic conditions in advance of the section are unsafe.

2. In combination, a section of railway track, means for supplying train governing current to said section when and only when the section is occupied by a train and for normally starting the supply of such current as soon as a train enters the section, and means for delaying the supply of said current to the section when a train enters the section if the section next in advance is occupied.

3. In combination, a section of railway track, means for supplying train governing current to the rails of said section when and only when the section is occupied by a train and for normally starting the supply of such current to the rails as soon as the train enters the section, and means for delaying the supply of such current when a train enters the section if traffic conditions in advance of the section are unsafe.

4. In combination, a section of railway track, means for supplying periodically interrupted alternating train governing current to the rails of said section when and only when the section is occupied by a train and for normally starting the supply of such current to the rails as soon as a train enters the section, and means for delaying the supply of such current when a train enters the

section if traffic conditions in advance of the section are unsafe.

5. In combination, a section of railway track, a track circuit including a normally energized track relay for said section, means for supplying train governing current to said section when and only when said track relay is deenergized and for normally starting the supply of such current as soon as the track relay becomes de-energized, and means for delaying the supply of said current when said track relay becomes de-energized if traffic conditions in advance of said section are unsafe.

6. In combination, a section of railway track, a signal for said section capable of indicating proceed, caution and stop, means for supplying train governing current to said section when and only when the section is occupied by a train and for starting the supply of such current as soon as a train enters the section if said signal indicates proceed, and means for delaying the supply of such current when a train enters the section if said signal indicates caution.

7. In combination, a section of railway track, a track circuit for said section including a normally energized track relay, a signal for said section capable of indicating proceed, caution and stop, means including a normally de-energized coding device for supplying train governing current to the rails of said section, a controlling circuit for said coding device including in series a back contact of said track relay and a contact closed when said signal indicates proceed but not when it indicates caution, a slow-releasing relay controlled by a front contact of said track relay, and a branch around the said contacts in said controlling circuit and including a back contact of said slow-releasing relay.

8. In combination, a section of railway track, a track circuit for said section including a normally energized track relay, a signal for said section capable of indicating proceed, caution and stop, a slow-releasing relay having a back contact and energized or de-energized according as said track relay is energized or de-energized, means including a normally de-energized coding device for supplying train governing current to the rails of said section, and means operating when a train enters said section to set said coding device into operation as soon as the back contacts of said track relay close if said signal indicates proceed, but to delay the operation of said coding device until the back contact of said slow-releasing relay closes if said signal indicates caution.

9. In combination, three successive sections of railway track, signals for said sections controlled in such manner that when the signal for the forward section indicates stop the signals for the intermediate and rear

sections both indicate caution, means for each of the intermediate and rear sections for supplying train governing current to the section when and only when the section is occupied by a train and for normally starting the supply of such current as soon as a train enters the section, and means for de-

laying the supply of train governing current to the intermediate section when a train enters such section if the signal for such section indicates caution. 10

In testimony whereof I affix my signature.

ROBERT M. GILSON.
